UNITED STATES PATENT OFFICE.

MOSES D. HEYMAN, OF OZONE PARK, NEW YORK, ASSIGNOR TO FELIX HERTZ, OF NEW YORK, N. Y.

PROCESS AND TOOL FOR MAKING LEATHER BUTTONS.

Application filed July 11, 1922. Serial No. 574,238.

To all whom it may concern:

Be it known that I, Moses D. HEYMAN, a citizen of the United States, and a resident of Ozone Park, county of Queens, and 5 State of New York, have invented certain new and useful Improvements in Processes and Tools for Making Leather Buttons, of which the following is a specification.

This invention relates to an improved 10 process and apparatus for use in making novelty buttons from strip material, with special reference to leather as used for ornamental and utilitarian purposes on the outer clothing of individuals, such buttons 15 presenting a pleasing appearance, and being substantially indestructible and convenient to handle.

One of the objects is to define a peculiar 20 manner in which the strip material is interlockingly coiled and knotted to produce a certain preferred appearance of the body and an integral eye, the same constituting a definite process as will later become apparent.

25 Another purpose is to provide an apparatus by which the button formation is secured in its initial stage and duplicate results invariably attained, thus overcoming the most difficult step in the weaving of the 30 button.

In the past this final step was accomplished with the hands, necessarily slow and painful, but with the aid of this simple apparatus a worker's hands are protected 35 from bruises, cuts and calli and the output of buttons is increased.

These and other like objects are secured by the novel process and mechanical device hereafter described and shown in the accompanying drawing, forming a material part 40 of this disclosure, and in which:

Figure 1 is a perspective view of a strip or thong of leather from which a button is formed.

45 Figure 2 is a similar view of the same showing the stage in which the leather thong has been woven before application to the apparatus.

Figure 3 illustrates this application in 50 fragmentary form.

Figure 4 is a view showing the result attained on the tool or jig; this being the completed button except for the final form.

Figure 5 is a perspective view showing

the button after passing thru compressing 55 dies.

Figure 6 is a view of the apparatus as applied to a table.

Figure 7 is a plan view of the tool in a closed position.

Figure 8 is a similar view of the same shown open.

Figure 9 is a side elevational view shown in an open position.

In the construction of the button about to 65 be disclosed, a single thong or narrow strip 15 of thin flexible leather, shown in Fig. 1, is the only article used, the strip varying in dimensions with respect to the size of the button and colored or left in its natural 70 state as preferred.

The finished button, illustrated in Fig. 5, shows a round body having an arched outer surface, a substantially flat base and an integral eye extending centrally therefrom.

The face has the appearance of four distinct segments radiating from the center and has a polished surface produced by the dies in which it is heavily compressed in its final stage.

The strip is first soaked in water until 80 pliable and then is woven by hand to the form shown in Figure 2, which provides a double knot having a looped opening 16 thru which the loop 17 must be drawn to 85 complete the weaving of the button.

Mounted on a table 20 are a plurality of tools or jigs arranged along one or both sides and enough space is allowed between them for the convenience and comfort of the operators.

The loop 17 of the partly formed button shown in Fig. 2 is placed upon a rigid upstanding member 21, provided with relatively small upright lugs 22, which form a 95 seat between them for the loop 17. The closely interwoven portion 18, which eventually forms the body of the button, is brought over in the direction of the arrow 23 see Fig. 3 and pushed downward over the 100 loop 17, the result being as in Fig. 7.

The treadle 24, pivotally mounted at 25 to the bar 26, is pressed downward with the foot thus imparting movement to the rod 27, which in turn produce a similar motion in 105 the arms 28 of bell-crank levers having a common pivot 29 arranged on opposite sides thereto.

The upper ends of the bell-crank are semi-cup shaped, as at 30, and are so arranged that the lowermost position of the treadle brings their open faces 31 in juxtaposition, thus forming a cup completely surrounding the upright member 21, which is centrally located and rigid therebetween.

The knot of leather being positioned on the member 21 is thus compressed and compactly formed as illustrated at Fig. 7, the loop 17 projecting therefrom.

When pressure on the treadle 24 is relieved the springs 32, fastened to lugs 33 on the cup members 30 at one end, and to any stationary portion, as the angle 34, at the other, will return the parts to an open position allowing the removal of the button blank.

The button is then placed in dies under very high pressure and the resultant finished product is the commercial article as shown in Fig. 5. The loop or eye 17 is used in attaching the button to the garment and the body 18 presents a highly polished and decorative appearance for sport clothes and similar wearing apparel.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. A method of making a leather button with a loop shank, comprising the interweaving of a strip upon itself, bringing a marginal loop of the weave opposite an intermediate mesh of the weave, and pressing the loop upon the end of a rigid outstanding member to force it through said mesh and contract the weave around the stem of the loop.

2. The method covered by claim 1, comprising compressing the woven body externally while the loop is held projected by said outstanding member.

3. The process covered by claim 2 characterized by a further final compression under high pressure of the woven body between forming dies.

4. A button forming apparatus comprising a central rigid projecting member, forming cups pivotally arranged on a fixed common center, at the base of said member, said cups having complementary faces, means causing the normal separation of said faces, and means for placing said faces in juxtaposition.

5. An apparatus for forming integral leather buttons comprising a rigid projecting forming element, semi-cupshaped members having a common pivot at the base of said element and open at their adjacent sides, an integral arm arranged substantially at right angles to each of said cupshaped members, springs for keeping apart the open faces of said cupshaped members, and means for closing said members against the pressure of said springs to surround said forming element.

6. A button forming apparatus, comprising two bell crank levers pivotally arranged on a common axis, each having a power arm at one end and a semi-cupshaped member at the other, spring means for holding said cupshaped members apart, treadle means for overcoming said spring means, and a fixed centrally supported rigid projecting element, arranged to have its base entirely encircled by the mentioned cupshaped elements when their complementary faces are juxtapositionally placed.

7. The process of making a button from a single leather strap consisting of knotting the strap after moistening, to present a loop inserting the bight of the loop through a portion of the knot to form an eye, subjecting the knot to moderate pressure between dies thereby roughly forming the button including the eye, and finally finish forming the button in dies under pressure approximating five tons.

8. The process of making a leather button from a single strap consisting of moistening the material until flexibility is attained, forming a double knot in the strap, including a central loop which will constitute an extending eye, and subjecting the blank thus formed to a relatively heavy pressure between highly finished dies.

In testimony whereof I have signed my name to this specification.

MOSES D. HEYMAN.
